United States Patent Office

Des. 221,522
Patented Aug. 24, 1971

221,522

SHIPPING CONTAINER

Oscar W. Meller, Akron, Edsel F. Moffitt, Tallmadge,
and Frank C. Morse and Walter F. Sprick, Akron,
Ohio, assignors to Goodyear Aerospace Corporation,
Akron, Ohio

Filed Jan. 16, 1970, Ser. No. 20,952

Term of patent 14 years

Int. Cl. D9—04

U.S. Cl. D9—246

FIG.-1

FIG.-2

FIG. 3

FIG. 4

FIG. 1 is a front or rear elevation view, both views being identical, showing full fabric closures on our shipping container;

FIG. 2 is a top plan view;

FIG. 3 is a bottom plan view wherein the base is a smooth, plane panel; and

FIG. 4 is side elevational view.

The top and sides are corrugated panels, one side meeting the base at a right angle while the other side meets the base at an oblique angle.

We claim:

The ornamental design for a shipping container, as shown and described.
